CLAIM

The ornamental design for a container for liquids or the like, substantially as shown.

DESCRIPTION

FIG. 1 is an elevational view of a container for liquids or the like showing our new design;
 FIG. 2 is a top plan view;
 FIG. 3 is a bottom plan view; and
 FIG. 4 is an enlarged sectional view taken along line 4—4 of FIG. 1.

*Fig. 2.**Fig. 1.**Fig. 4.**Fig. 3.*
